(57) **CLAIM**

The ornamental design for a high-speed, spill-proof cooking container, as shown and described.

DESCRIPTION

FIG. 1 is a perspective view of a new and ornamental design for a high speed, spill-proof cooking container.

FIG. 2 is a side elevation view thereof.

FIG. 3 is a top plan view thereof.

FIG. 4 is a front elevation view thereof.

FIG. 5 is a bottom view thereof.

FIG. 6 is a cross-sectional view taken through line 6—6 of FIG. 3.

FIG. 7 is a bottom plan view of the cover of the high speed, spill-proof cooking container, shown separately for ease of illustration; and,

FIG. 8 is a side elevation view thereof.
